DISC REFINER

Herman W. Steiniger, Springfield, Ohio, assignor to The Bauer Bros. Company, Springfield, Ohio, a corporation of Ohio

Filed Oct. 15, 1958, Ser. No. 767,433

7 Claims. (Cl. 241—79)

This invention relates to disc refiners and more particularly to an improved pulp refining system for use on pulp suspensions which have a tendency to foam.

Certain types of pulp suspensions have a tendency to produce foam, either in the form of large air bubbles or small bubbles which produce a heavy lather. The foam can reach a thickness of several feet, the fibers being suspended in the foam. Since the foam is principally air, it is impossible for a conventional pumping system to handle it and the tanks and vats handling such a suspension have a tendency to overflow. This means that the air which creates the foam must be excluded or evacuated in order to make it possible to refine stock with a foaming tendency.

Previous devices for handling this type stock are relatively inefficient. They generally consist of slow speed refiners which are actually not suitable for completing the defibering of a pulp suspension since most of them have a tendency to cut the fibers. Moreover, their rotating elements generally operate submerged in the stock being refined, producing high friction and consuming large amounts of power in the process.

In the development of the invention recognition has been taken of the fact that a double disc refiner operating at high speeds is an excellent device for defibering since the fiber bundles tend to align themselves in a radial direction and the teeth of the rotating disc tear off individual fibers from the bundles with little tendency for cutting. The system of the invention in its preferred form employs contained discs operating in a housing with a sealed feed and discharge, means being provided for excluding and evacuating air from the stock being processed. The discs are so related to the stock flow to enable their operation at high speeds with substantially no turbulence resulting. Substantial economy and efficiency of operation results in the use of the invention system and a high quality product is insured.

A primary object of the invention is to provide improvements in refining systems for operating on pulp suspensions which have a tendency to foam whereby such systems may be more economically manufactured, more efficient and satisfactory in use, adaptable to wide variety of applications and be unlikely to get out of repair.

A further object of the invention is to provide an improved refining system having a sealed feed and discharge which avoids entrainment of air in the stock being processed.

Another object of the invention is to provide a pulp refining system which effectively excludes and evacuates air from the pulp stock preliminary to deliver to a paper making machine or the like.

An additional object of the invention is to provide an improved disc refiner system for producing high quality pulp at minimum cost wherein double refining discs are employed in conjunction with a sealed feed and discharge.

Another object of the invention is to provide improvements in disc refiners by applying means for controlled evacuation of air from the refined stock.

A further object of the invention is to provide an improved refiner and system possessing the advantageous structural features, the inherent meritorious characteristics and the mode of operation herein mentioned.

With the above and other incidental objects in view as will more fully appear in the specification, the invention intended to be protected by Letters Patent consists of

2

the features of construction, the parts and combinations thereof, and the mode of operation as hereinafter described or illustrated in the accompanying drawings, or their equivalents.

Referring to the accompanying drawing wherein is shown one but obviously not necessarily the only form of embodiment of the invention,

FIG. 1 is a generally diagrammatic view illustrating a pulp refining system as provided by the invention; and

FIG. 2 is a diagrammatic illustration of a modification 10 of the invention system as shown in FIG. 1.

Like parts are indicated by similar characters of reference throughout the several views.

The invention can be best described with reference to the drawings. A double disc refiner 1 is shown to include opposed discs 2 and 3 which are rotatable in opposite directions. The disc 2 is centrally mounted about one end of a hollow shaft 4 which is the drive shaft of a motor 5. The refiner base 6 has vertical standards 7 to either end of motor 5 which mount bearings 8 for the shaft 4.

The disc 3 is centrally mounted to the drive shaft 9 of a motor 10 coaxial with the shaft 4. The shaft 9 is similarly supported in bearings 11 in spaced vertical standards 12 on the base 6. Means 13 are diagrammatically illustrated in connection with the shaft 9 for axial adjustment of the shaft and connected disc 3 relative disc 2 in a manner which is obvious and which constitutes no part of the present invention.

The opposed faces of the discs 2 and 3 are dish shaped. 30 The hollow shaft 4 communicates with the space between the discs 2 and 3 at its outlet end and is provided with a rotary union 15 at its inlet end through which stock is delivered under pressure.

A housing 16 contains the discs 2 and 3 and mounts 35 about the respective shafts 4 and 9. The only outlet provided from the housing 16 is through an opening at its bottom defined by a tube 17 sealed thereabout and extending to connect into a stock chest 18, which is pressure tight. Access panel 19 seals an opening to the chest 18.

40 A vacuum pump 14, schematically shown, has an evacuation tube 21 opening into the top of the chest 18. A centrifugal discharge pump 22 connects into the bottom of the chest 18, while a delivery tube 23 leads from the pump 22 to subsequent fiber treating equipment in the 45 preferred application of the invention.

A recirculation tube 24 connects from the tube 23 into the upper portion of the stock chest. The tube 24 has a valve 25 therein controlled by a level sensing device 26 which is float controlled to selectively maintain the valve 50 25 open or closed, depending on the level of the stock in the chest 18, as will be described.

In the use of the invention system stock is delivered through shaft 4 under pressure to the space intermediate 55 oppositely rotating discs 2 and 3. Since the feed line is sealed, entrainment of air in the pulp slurry or stock is avoided. The pulp is passed between the discs which tear off individual fibers from the fiber bundles in the stock. The stock, thus modified, is slung radially into housing 16 to drop by gravity through the sealed feed passage 17 into 60 the stock chest.

The level sensing device 26 in the stock chest is so adjusted that a certain space is to be maintained above the refined stock falling into the chest. The connected vacuum pump 14 is operated to induce a partial vacuum in 65 this space above the stock. As the refined stock falls into the chest, the vacuum induced therein causes the air within the fiber material to be drawn off. This is facilitated by the free fall of the refined material. If the level of the stock should fall, the device 26 operates to open valve 70 25 to bring sufficient refined material normally being delivered by the pump 22 to subsequent fiber treating equipment.

ment back into the chest 18 to re-establish the required level of the stock therein. The fact the discs 2 and 3 are not immersed in the stock in operation enables their high speed operation with minimum power loss. The sealed feed and discharge insures that no outside air is drawn in to cause undue foaming or turbulence as the stock is refined and delivered. Foaming is reduced to a minimum and the processing of the fibers is smooth and efficient. The controlled vacuum in the stock chest insures maximum air evacuation.

The above system is particularly desirable when applied to the refining of pulp with tendencies to foam excessively but its application is, of course, not so limited. The smooth continuous flow operation which is provided for stock having inherent tendency to foam enables the production of a pulp, both quantity-wise and quality-wise, representing a distinct advance in the art.

FIG. 2 of the drawings shows a modification of the system of FIG. 1. In this embodiment the structure of the refiner proper is identical through to the discharge tube 17. Here a centrifugal separator 30 is connected in the discharge tube 17' preliminary to the delivery of the refined material from the discs to the stock chest 18'. The centrifugal separator has a tube 31 in its top open to the atmosphere. The separator operates on material passing therethrough to evacuate whatever air is entrained through the tube 31. From the separator the refined material is delivered into the sealed stock chest 18' from which it is drawn and delivered to subsequent fiber treating equipment by a pump 22' connecting into the bottom of the stock chest by a tube 21'.

Thus, it will be readily seen that the present system will positively and effectively control any stock that will be likely to produce problems of foaming in operation. It is efficient, simple and requires a minimum of power.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific features shown, but that the means and construction herein disclosed comprise but one of several modes of putting the invention into effect, and the invention is therefore claimed in any of its forms or modifications within the legitimate and valid scope of the appended claims.

Having thus described my invention, I claim:

1. A pulp refiner system including, a sealed housing having a feed and gravity discharge means sealingly connected therein, means for receiving stock from said feed means within said housing, refining it and delivering it to said gravity discharge means, a stock chest having a sealed connection to said discharge means and means for evacuating air from the refined stock as it is delivered from said discharge means to said chest, said last named means including a centrifugal separator means in said gravity discharge means intercepting the refined stock.

2. A pulp refiner system including, a sealed housing, a pair of cooperative refiner discs oppositely rotatable therein, a gravity discharge means having a sealed connection to said housing, a pressure feed means connected in said housing for delivery of stock to said refiner discs to be refined thereby and gravity discharged through said discharge means, a sealed receptacle for the stock delivered through said discharge means having a pressure tight connection to said gravity discharge means, means for selectively recirculating stock withdrawn from said receptacle

for maintaining a predetermined stock level in said receptacle to maintain a predetermined space therein and vacuum creating means operatively connected into the space in the top of said receptacle to induce an evacuation of air entrained in said stock as it drops into said receptacle.

3. The structure as set forth in claim 2 characterized by drive means mounting said discs, one of said drive means being hollow and constituting feed means for delivery of stock between said discs for refining.

4. A pulp refining system including a sealed operating housing having a feed means connected therein in sealed relation thereto, a gravity discharge means from said housing, refiner means in said housing receiving stock from said feed means for delivery after refining through said gravity discharge means, a stock chest, said gravity discharge means delivering the refined stock to said stock chest, means selectively recirculating stock withdrawn from said stock chest for maintaining a predetermined stock level in said chest, providing a space in the upper portion thereof, said refined stock free falling through said space on delivery to said chest, and means connected in said upper portion of said chest evacuating air from the refined stock during its free fall.

5. The structure as set forth in claim 4 wherein said refiner means are provided by opposed dish-shaped discs and said feed means connects intermediate said discs in the dished portions thereof.

6. A pulp refiner, including an enclosed housing, refiner means in said housing, means delivering stock under pressure to said refiner means in said housing, said housing having a single outlet, a stock chest in closed communication with said outlet, means selectively recirculating stock withdrawn from said stock chest for maintaining a predetermined high stock level in said chest providing for a free gravity fall of stock from said outlet through at least a portion of said chest, and means applying a vacuum to the space above the stock level in said chest.

7. A pulp refiner, including a housing having an enclosed chamber means to deliver stock under pressure to said chamber, a single outlet from said chamber, a double disc refiner in said chamber receiving the delivered stock under pressure between its discs and discharging it peripherally outward into said chamber, the varying fluids and solids comprising or accompanying the refined stock having a common escape from said chamber by way of said single outlet, a stock chest in closed communication with said outlet, and means applying a vacuum to the upper part of the interior of the stock chest, said vacuum being exerted upon the stock during free fall from said outlet into the chest.
